US00D829336S

(12) **United States Design Patent** (10) Patent No.: **US D829,336 S**
(45) Date of Patent: **** Sep. 25, 2018**

(54) **AUTOMATED ASSAY SYSTEM**

- (71) Applicant: **Meso Scale Technologies, LLC.**, Rockville, MD (US)
- (72) Inventors: **Jacob N. Wohlstadter**, Potomac, MD (US); **Rodger Darin Osborne**, Stuart, FL (US); **Bandele Jeffrey-Coker**, Darnestown, MD (US); **Aaron Leimkuehler**, Clair, PA (US); **Manish Kochar**, Rockville, MD (US); **Kenneth Page**, Martinsburg, WV (US)
- (73) Assignee: **Meso Scale Technologies, LLC.**, Rockville, MD (US)

(**) Term: **15 Years**

(21) Appl. No.: **29/577,664**

(22) Filed: **Sep. 14, 2016**

(57) **CLAIM**

The ornamental design for an automated assay system, as shown and described.

DESCRIPTION

FIG. 1 is a perspective view of the automated assay system showing our new and ornamental design;

FIG. 2 is a front view thereof;

FIG. 3 is a back view thereof;

FIG. 4 is a side view thereof;

FIG. 5 is an alternate side view thereof; and,

FIG. 6 is a top view thereof.

The portions of the automated assay system shown in broken lines in the figures form no part of the claimed design.
